UNITED STATES PATENT OFFICE.

LOUIS C. POIRIER, OF MERRILL, WISCONSIN.

ANTENNA FOR RADIO RECEIVING SETS.

Application filed February 14, 1927. Serial No. 168,040.

This invention relates to antenna for radio receiving sets.

Objects of this invention are to provide a novel form of antenna which is non-directional, which will protect the insulated support under all weather conditions against inadvertent short circuiting or grounding, and which has such a construction that the guy wires may act not only in the capacity of guy wires, but also may be used to supplement the antenna and to form a portion therewith, if desired.

Further objects are to provide a novel form of antenna which has a low wind resistance, which has sufficient cross sectional area, and which has a low electrical resistance.

An embodiment of the invention is shown in the accompanying drawings in which:—

Figure 1 is a side elevation showing the antenna in position;

Figure 2 is a sectional view through the antenna;

Figure 3 is a view from the underside of the apparatus;

Figure 4 is a fragmentary sectional view on the line 4—4 of Figure 3.

Referring to the drawings, it will be seen that the antenna comprises a sheet metal cone 1 which is provided with a metal supporter 2. Preferably, the spider and the cone are each formed of copper, to have the minimum resistance. The arms of the spider are riveted, as indicated at 3, to the cone at spaced points to secure the maximum strength. If desired, one of the arms may be provided with a binding post 4 for the lead-in wire.

The spider is provided with a reenforcing upper metal plate 5, as shown most clearly in Figure 4, through which the attaching headed bolts 6 pass. These bolts pass through insulating sleeves 7, such sleeves passing through a flanged coupling 8. The coupling 8 may be made of cast iron or other suitable material and is provided with a central threaded aperture 9 for the reception of the upper threaded end of the supporting pipe 10. The spider 2 is held out of contact with the coupling by means of an insulating disc 11 (see Figure 4) and on the underside 50 a plurality of small insulating washers 12 are provided for the bolts 6, preferably a metal washer 13 being used in conjunction with each of the bolts, as shown in Figure 4.

These bolts 6 are adapted to receive the upper ends of the guy wires 14 and to thus electrically connect the guy wires with the

antenna, so that the guy wires form a portion of the antenna. The lower ends of the guy wires are secured to an insulating member 15 which, in turn, is connected to the attached portions 16 of such guy wires. In this way, the lower ends of the guy wires are insulated while the upper ends are electrically connected to the cone.

It will be seen that by this construction a very extensive area is presented to the wireless waves and, in addition, the guy wires themselves supplement the action of the cone and form a portion of the antenna. If, however, it is not desired to use the guy wires in the capacity described above, the insulators 15 may be located closely adjacent the upper ends of the guy wires so that they are electrically distinct from the cone.

It will be seen that a novel form of antenna has been provided which is non-directional, which is so constructed that it completely houses the insulated support and protects such support from short circuiting or grounding the cone under all weather conditions. From reference to Figure 2, it will be seen that the cone acts as a housing for the upper end of the support and the insulating washer or disc.

From reference to Figure 4, it will be seen that the disc 11 extends across the upper open end of the threaded aperture 9 of the coupling 8 and, consequently, prevents contact of the upper end of the supporting pipe with any metal portion of the antenna system, although the metal pipe may be threaded a considerable distance at its end.

It will be seen further that the antenna is of very simple and substantial construction, and may be cheaply produced.

Although the invention has been described in considerable detail, such description is intended as illustrative rather than limiting the invention may be variously embodied and as the scope of such invention is to be determined as claimed.

I claim:

1. An antenna for radio work comprising an extensive sheet metal member having an insulated coupling located on its underside, a metal support secured to said coupling, and a plurality of bolts attaching said member to said coupling and adapted to receive guy wires, said bolts being electrically connected to said member and insulated from said coupling.

2. An antenna for radio work comprising

an extensive sheet metal member having an insulated coupling located on its underside, a metal support secured to said coupling, and a plurality of bolts attaching said member to said coupling and adapted to receive guy wires, said bolts being electrically connected to said member and insulated from said coupling, a plurality of guy wires electrically and mechanically connected to said bolts, and insulating attaching members secured to the lower end of said guy wires.

3. An antenna comprising a conical sheet metal member having an open lower end, a metal spider secured to said member and lo-

cated within said member and spaced upwardly from the open lower end, an insulating plate located below said spider, a coupling having a threaded support-receiving aperture and located below said plate, a plurality of clamping bolts passing through said coupling, plate and spider and insulated from said coupling and electrically connected to said plate, said plate extending across the aperture in said coupling.

In testimony that I claim the foregoing I have hereunto set my hand at Merrill, in the county of Lincoln and State of Wisconsin.

LOUIS C. POIRIER.
